(57) **CLAIM**

The ornamental design for a skin lotion bottle, as shown and described.

DESCRIPTION

FIG. 1 is a top, rear perspective view of a skin lotion bottle showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a sectional view thereof, taken along section line 8—8 in FIG. 2.

The broken lines shown in the drawings are included for the purpose of illustrating environmental structure that forms no part of the claimed design.
